UNITED STATES PATENT OFFICE.

HORACE M. ALLEN, OF DETROIT, MICHIGAN.

ADJUSTABLE FOOT-REST OR SHELF FOR RADIATORS.

1,004,959.

Specification of Letters Patent.

Patented Oct. 3, 1911.

Application filed November 10, 1910. Serial No. 591,583.

To all whom it may concern:

Be it known that I, HORACE M. ALLEN, a citizen of the United States, residing at Detroit, county of Wayne, State of Michigan, have invented a certain new and useful Improvement in Adjustable Foot-Rests or Shelves for Radiators, and declare the following to be a full, clear, and exact description of the same, such as will enable others skilled in the art to which it pertains to make and use the same, reference being had to the accompanying drawings, which form a part of this specification.

This invention relates to foot rests for radiators.

It has for its object an improved adjustable bracket attachment for radiators adapted to be secured to the radiator at any place between the top and the bottom thereof, and arranged at the will of the user as a foot-rest, bracket, shelf or table. In the drawings it is shown attached to the radiator intermediate its top and bottom in the place where it is especially adapted for use as a foot rest.

In the drawings:—Figure 1, is a perspective of the complete rest attached to a radiator coil. Fig. 2, is a side elevation partly in section indicating the location and arrangement of the securing means by which the bracket is attached to the radiator. Fig. 3, is a perspective of the upper connection. Fig. 4, is a perspective of the tie bar used with the upper connection. Fig. 5, is the front member of the lower connection. Fig. 6, is a latch used in the lower connection. Fig. 7, is a rear clamp member of the lower connection. Fig. 8, is the bolt used with the rear clamp of the lower connection. Fig. 9, is a detail partly in section showing the adjustable brace and its connection with the foot rail. Fig. 10, is a detail showing the end of the top tie bar in connection with the top rail of the bracket. Fig. 11, is an end view of the foot rail. Fig. 12, is a longitudinal section of part of the foot rail showing one end thereof. Fig. 13, is an elevation showing one end of the foot rail.

The bracket or shelf is an open-work frame of any desired design provided with a comparatively large tubular foot rail 1 at the lower or outer edge thereof and a smaller hinge rail 2 at the upper or inner end thereof. The two rails 1 and 2 are tied together

by any suitable side members 6 and included grille work, preferably metal and open work, as shown in Fig. 1. The top rail is in hinge connection or pivotal connection with a pair of tie bars 3 each of which has an eye 4 at its outer terminal that engages over the rail 2 which is tubular; the top rail 2 incloses a rod 7 that is centrally located within it; the side arms 6 are provided with projections 8 that engage through slots in the tubular member 2 and terminate with eyes through which the central rod 7 engages, and which is held central with respect to the tube by shoulders 9 on the end of each side arm 6. The foot rail 1 also has a central rod 10 and an eccentric rod 11 located within it at one side of the rod 10. The side arm 6 engages through a slot in the tubular member 1 and terminates with an eye through which the central rod 10 engages; the rod 10 is held central to the tubular member 1 by caps 12 at each end, which caps 12 also support the eccentric rod 11. Ornamental finishing terminals 44 are secured to the end of the tube 1. A brace 13 curved on an arc whose radius of curvature is substantially equal to the length of the side rod 6 terminates with an eye that engages over the rod 11 and the end of the brace 13 engages through a slot 14 in the rail 1. The brace member 13 is a two-part telescoping member; the front portion 15 is hollow and is provided with serrations 46 on the inner run of the arch; the second part of the brace 16 telescopes in the external front member and is also provided with serrations 47 on the inner run of its arch. This brace engages through a housing member 30 which is arranged to be held securely to the radiator at the proper place between the top and the bottom thereof, while the top-holding tie 3 is arranged to be secured to a holding member that is attached to the radiator between the top and the bottom thereof and above the member 30.

The top-holding member consists of two wedge-like clamps 22 and 23 held together by a tie rod 24 and nut 25; the clamps are of suitable shape to engage between the adjacent loops of the radiator. The rearmost of these wedge clamps 23 is provided with a headed stud 26 over which engages a key-hole slot 27 in the tie member 3. The forward end of the tie member 3 is held to the member 22 by a binding screw 28. This makes

a holding structure for the top of the bracket that is adjustable to various sizes and styles of radiator loops and is so located with respect to the loops as to be almost entirely hidden or concealed, and upon which the tie member 3 can be properly located and securely held, irrespective of the spacing of the wedge members from each other.

The lower holding member consists of a forward wedge-shaped member 29 provided with a latch housing 30, a rear clamp 31 and screw rod 32; the rear clamp 31 engages across the back of two or more of the radiator loops with the rod 32 extending between adjacent loops and with the forward wedge member engaging between the same adjacent loops. The housing 30 contains a gravity latch 33 adapted to drop into engagement with the serrations in the brace members 15 and 16. The gravity latch 33 is provided with a bail or loop 34 under which engages a pivoted lever 35. The lever 35 is pivoted to a knuckle member 36 which is itself pivoted at 37 to the housing 30. One end 38 of the lever 35 extends to the rear under the knuckle member 36 and when the front end of the lever 35 is lifted the rear end 38 acts as a strut to hold the lever in its lifted position and to hold the latch 33 out of engagement with the serrated members 15 or 16. As the serrated members are arranged one at each end of the bracket and it is sometimes desirable, when adjusting the inclination of the bracket to disengage the latch 33 and the brace and continue it in its disengaged condition, this may be accomplished by lifting the front end of the levers 35 until the strut members 38 are in position to hold the levers in their lifted position when the brace members of the bracket become entirely free and the inclination may be changed and the free edge of the bracket dropped. When the ends of the levers 35 are dropped and the latch 33 is free to engage the serrations the latch will automatically engage and hold the bracket in position as the lower end is swung outward from the foot of the radiator.

The inner serrated part 16 of the bracket is held from escaping from the outer member by a head 39 which abuts against a collar 40 when the brace is distended, and is held in its distended position by a side spring catch 41 that spreads from the member 16 and abuts against the end of the member 15 when in expanded condition. The function of the latch 41 is to hold the outer member 46 of the telescoping brace in extended position when the inner brace member is drawn out beyond the catch, which, when drawn out with the brace member, springs out and acts as an abutment upon which the outer member may rest by gravity. This compound brace is used in order that the foot rest may be used with either narrow or wide

radiators and that the brace when expanded may be long enough to lift the shelf to a fully horizontal position, and short enough when contracted to allow the shelf to drop to a vertical condition with the brace extending no farther back than the rear plane of the radiator loops.

What I claim is:—

1. In combination with a radiator having a plurality of loops, a foot-rest or bracket, supporting members adjustable vertically between said radiator loops, the said foot-rest or bracket being pivoted to the upper supporting member, a brace therefor comprising two telescoping portions, means for securing the two portions in extended position with reference to each other, and means for securing the brace in extended position, substantially as described.

2. In combination with a radiator having a plurality of loops, a bracket pivoted thereto, a supporting brace therefor, pivoted at one end to said bracket, said brace comprising two telescoping parts adapted to engage between the radiator loops, a latch housing having an aperture through which the brace is adapted to pass, a gravity catch adapted to be raised from or dropped upon the outer telescoping part of the brace, and a spring catch engaging in the inner telescoping member and adapted, when the inner member is drawn out beyond the location of the catch, to spring out and form an abutment which holds the outer telescoping member in extended position, thereby swinging said bracket outwardly accordingly, substantially as described.

3. In combination with a radiator provided with a number of loops, a bracket, a tie member carried by some of said loops and pivotally supporting said bracket and said tie member, being provided with a circular slot, a pair of wedge-like clamps adapted to engage between the radiator loops, a tie rod passing through said wedged clamps, a nut running on said rod and adapted to cause the clamps to approach each other and to be wedged securely in place between the radiator loops, and a binding screw engaging in the clamp member farther from the bracket, and having a head which is adapted to pass through the aperture and slide in the slot, thereby holding the said top tie member in position on the said clamps, substantially as described.

4. In combination with a radiator having a plurality of loops, a horizontally disposed clamp located between the top and the bottom of certain of the loops, means for adjustably attaching said clamp on said loops, a swinging bracket hinged to said clamp along its upper edge, a latch housing member attached to said loops adjacent the lower edge of said bracket member, a telescoping brace member pivoted at its upper end to

said bracket, and slidably engaging through
said latch housing member, and a normally
inactive gravity catch carried in said hous-
ing member, and adapted to engage said
brace member when it is swung out to its
outer position, thereby locking it in such
position, substantially as described.

In testimony whereof, I sign this speci-
fication in the presence of two witnesses.

HORACE M. ALLEN.
